US0D1081405S

(12) **United States Design Patent** (10) Patent No.: **US D1,081,405 S**
(45) Date of Patent: ** Jul. 1, 2025

(54) **BASE FOR A MEASUREMENT DEVICE**

(71) Applicant: **PMT TECHNOLOGIES (SUZHOU) CO., LTD.**, Suzhou (CN)

(72) Inventors: **Zihuan Shao**, Jiangsu (CN); **Qiang Huang**, Jiangsu (CN); **Dayong Tai**, Jiangsu (CN)

(**) Term: **15 Years**

(21) Appl. No.: **35/521,160**

(22) Filed: **Apr. 16, 2024**

(80) **Hague Agreement Data**

Int. Filing Date: **Apr. 16, 2024**

Int. Reg. No.: **DM/237455**

Int. Reg. Date: **Apr. 16, 2024**

Int. Reg. Pub. Date: **Jun. 7, 2024**

(30) **Foreign Application Priority Data**

Jan. 8, 2024 (CN) 202430009689.9

(51) **LOC (15) Cl.** **10-04**

(52) **U.S. Cl.**

USPC **D10/103**; D8/396

(58) **Field of Classification Search**

USPC D10/46, 103, 121; D8/396

CPC G01B 21/045; G01B 5/008

See application file for complete search history.

Primary Examiner — George D. Kirschbaum

Assistant Examiner — Lillian Embrey

(57) **CLAIM**

The ornamental design for a base for a measurement device as shown and described.

DESCRIPTION

1. Base for a measurement device

1.1: Front

1.2: Back

1.3: Left

1.4: Right

1.5: TOP

1.6: Bottom

1.7: Perspective

1.8: Perspective shown in a first state of use

1.9: Perspective shown in a second state of use

1.10: Perspective shown in a third state of use

1 Claim, 5 Drawing Sheets
